UNITED STATES PATENT OFFICE.

EUGENE CHILDS, OF BOSTON, MASSACHUSETTS.

DESIGN FOR AN INFLATION-VALVE CASING.

SPECIFICATION forming part of Design No. 32,093, dated January 9, 1900.

Application filed November 17, 1899. Serial No. 737,377. Term of patent 14 years.

To all whom it may concern:

Be it known that I, EUGENE CHILDS, of Boston, (Roxbury,) in the county of Suffolk and State of Massachusetts, have invented and produced a new and original Design for an Inflation-Valve Casing, of which the following is a description sufficiently full, clear, and exact to enable those skilled in the art to which it appertains or with which it is most nearly connected to make and use the same.

The figure of the drawing which forms a part of this specification represents the design in perspective.

In the drawing, *a* designates a round or cylindrical stem which springs from the bottom of a head *b*, the outer surface of which has circular bands *c* *d* *e* formed on its outer surface, said bands being of different diameter and character, the band *c* being of frusto-

conical form, while the bands *d* and *e* are 20 flattened and of varying diameter.

f designates a circular depending flange springing from the bottom of the head and surrounding the upper part of the tube *a*.

g designates the closed or solid end of the 25 stem *a*.

Having described my invention, I declare that what I have invented and produced is—

The design for an inflation-valve casing as herein shown and described.

In testimony whereof I have signed my name to this specification, in the presence of two subscribing witnesses, this 31st day of October, A. D. 1899.

30 EUGENE CHILDS.
